US00D898884S

(12) **United States Design Patent** (10) **Patent No.:** **US D898,884 S**
(45) **Date of Patent:** **** Oct. 13, 2020**

(54) **FRAME FOR HVAC UNIT**

- (71) Applicant: **BARD MANUFACTURING COMPANY, INC.**, Bryan, OH (US)
- (72) Inventors: **Randall Price**, Bryan, OH (US); **Sean David Skiver**, Defiance, OH (US); **Dean F. Anderson**, Bryan, OH (US)
- (73) Assignee: **BARD MANUFACTURING COMPANY, INC.**, Bryan, OH (US)
- (**) Term: **15 Years**
- (21) Appl. No.: **29/693,531**
- (22) Filed: **Jun. 3, 2019**
- (51) LOC (12) Cl. **23-03**
- (52) U.S. Cl. **USPC D23/329**
- (58) **Field of Classification Search**
USPC D23/314, 317, 318, 320, 322, 325, 329, D23/342; D15/89, 91; D13/184
CPC G08B 13/08; F24F 1/62; F24F 1/56; F24F 1/58
See application file for complete search history.

(57) **CLAIM**

The ornamental design for a frame for HVAC unit, as shown and described.

DESCRIPTION

FIG. 1 is a first embodiment of a frame for HVAC unit in a perspective view;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 shows the frame for HVAC unit positioned on a wall mount HVAC unit;

FIG. 9 is a second embodiment of a frame for HVAC unit in a perspective view;

FIG. 10 is a front view thereof;

FIG. 11 is a rear view thereof;

FIG. 12 is a left side view thereof;

FIG. 13 is a right side view thereof;

FIG. 14 is a top view thereof; and,

FIG. 15 is a bottom view thereof.

In the drawings, the broken lines in FIG. 8 depict environmental subject matter and the other broken lines depict unclaimed portions of the design only and form no part of the claimed design.

1 Claim, 11 Drawing Sheets
